UNITED STATES PATENT OFFICE.

MERLE P. CHAPLIN, OF WHITE PLAINS, NEW YORK, ASSIGNOR TO WESTERN ELECTRIC COMPANY, INCORPORATED, OF NEW YORK, N. Y., A CORPORATION OF NEW YORK.

PRINTING TELEGRAPHY.

Application filed November 13, 1920. Serial No. 423,811.

To all whom it may concern:

Be it known that I, MERLE P. CHAPLIN, a citizen of the United States, residing at White Plains, in the county of Westchester, State of New York, have invented certain new and useful Improvements in Printing Telegraphy, of which the following is a full, clear, concise, and exact description.

This invention relates to printing telegraphy, and particularly to distributing mechanism utilized in such systems.

An object of the invention is to provide a distributor free from the defects inherent in use of rotating commutator brushes.

15 A further object of the invention is the provision of a distributor having incorporated therein mechanical means for controlling the release of the power shaft of the receiving printer.

20 In accordance with another object, the invention provides for the association of the distributing mechanism and the receiving printer in a unitary structure.

25 For accomplishing the above objects, the present invention provides a distributor mechanism arranged in conjunction with the receiving printer and forming a part thereof, utilizing a plurality of contacts designed to be actuated by means of an intermittently 30 revolving arm. The contacts are arranged concentrically, being adapted to be actuated in succession for distributing the character selecting units to the selector mechanism of the receiving printer in accordance with the 35 signal current impulses received from the distant station. Incorporated with the distributing mechanism is a mechanical means, such as, for example, a cam, which, for each revolution of the distributor arm effects the 40 release of the power shaft of the receiving printer.

The above and other objects of this invention, will be set forth in the following description and annexed claims, and will be 45 more readily understood by reference to the accompanying drawings, wherein Fig. 1 is a front view of a distributor designed in accordance with the present invention and having a portion thereof cross-sectioned for the 50 purpose of more clearly disclosing the invention, Fig. 2 is a side view of the mechanism disclosed in Fig. 1, Fig. 3 is a view taken along the line 3—3 of Fig. 1, Fig. 4

discloses the cam together with the connecting links for releasing the power shaft of 55 the receiving printer, while Fig. 5 discloses in schematic form the combination of the distributing mechanism disclosed in Fig. 1 and a portion of a receiving printer.

A receiving printer of the character with 60 which a distributor mechanism of the type hereinafter described is especially applicable, is disclosed in an application of Harry Pfannenstiehl, Serial No. 397,503, filed July 21, 1920, and since the above mentioned co- 65 pending application illustrates and describes in detail the various operations of a receiving printer, it is considered unnecessary to show a complete structure of the receiving printer as applied to the present invention, 70 but to show only so much of the apparatus as is necessary to a clear understanding of the invention. Obviously, however, a distributor of the character covered by this invention is applicable to types of receiving 75 printers other than that disclosed and described in the above mentioned co-pending application of Harry Pfannenstiehl.

Referring now to the drawing, there is 80 shown a distributor mechanism designed in accordance with the previously enumerated objects, comprising a plurality of contact springs 5. These springs are concentrically arranged on a face plate 10 by suitable screws such as 11. Plate 10 is secured to 85 posts 4, forming a part of the frame 7 by screws 2. Associated with the springs 5 is an auxiliary spring 13. The springs 5 and the auxiliary springs 13 are arranged in a unit with insulating material 14 and 15 interposed therebetween for the purpose of insuring a good insulation, the combination being in turn secured to the plate 10. At the free end of the springs 5 there is an adjustable contact screw 16 for regulating the 90 distance through which the spring 13 is required to move before making contact therewith. The spring 13, there being a similar spring provided for each of the springs 5, 95 is formed of a very rigid material so that upon the release thereof, it will instantly return to its normal position, thus giving a clean contact. Suitably arranged with the spring 13, and secured by the same screws 100 is an operating member 17. To the free end of the member 17 there is attached a pro- 105

jecting portion 18, which, as will be herein-after described, is arranged to be operated by an intermittently revolving arm for effecting the engagement of the contact 5 springs 13 and screw 16.

In order that the contact springs may be actuated in succession, an arm 19 is rigidly secured to a shaft 20. Normally the arm 19, together with the shaft 20 is held against 10 rotation by means of a stop member 21. This stop member 21 is mounted on the armature of a start magnet 22. Magnet 22, as in the usual distributors of the start-stop type, operates to release the arm 19 15 for permitting the contact springs to be actuated in succession. The energizing circuit of the start magnet 22 extends through a pair of contacts 23 and 24, which are normally in engagement due to the pressure of 20 the arm 19. Thus, the instant the arm 19 is released, the energizing circuit for the electro-magnet 22 is broken, due to the opening of contacts 23 and 24, which is thereupon prevented from being energized until 25 the contacts 23 and 24 are again completed by passage of the arm 19 thereover. Secured at a point intermediate the ends of the arm 19 is a knife or wedged shaped member 8. This member 8 is shaped in this 30 manner for the purpose of eliminating the retardation effect of the projections 18 on the springs 17.

For the purpose of eliminating as much 35 of the friction as possible between the shaft 20 and its bearings 25 and 26, suitable ball bearings 27 and 28 are provided. Secured to the bearing 26 by means of screws 29 is a face plate 31.

Intermediate the bearings 25 and 26 is 40 positioned a cam 34. This cam 34 is keyed to the shaft 20, and is thus revolved upon the release of the arm 19 due to the energization of the start magnet 22 which permits the shaft 20 to be driven through a 45 suitable friction clutch to be hereinafter described. The cam 34 is so arranged that for each revolution of the shaft 20 and following the transmission of the character selecting units, a lever 35 will be acted upon. The 50 lever 35 is rigidly secured to a shaft 36, at one extremity of which is keyed one part of a toggle joint, comprising members 37 and 38. By means of a spring 39 which has one end attached to the member 37 and the other 55 to an upright member 46, the member 37 is thus normally retained in engagement with a stop screw 40. Rigidly secured to the member 38 of the toggle joint is a block 41 arranged to be revolved about a shaft 45 60 mounted in the frame 42. Upon the engagement of the eccentric portion of the cam 34 with the lever 35, the shaft 36 will be revolved in the direction of the arrow. The movement of the shaft 36 in this manner 65 causes a similar action on the members 37

and 38 of the toggle joint, thus effecting a downward movement of the block 41. The block 41 thereupon moves to a position whereby a stop arm 43 is released. The release of the stop arm 43 permits, as will be 70 more clearly described, a shaft 44 to be revolved by power communicated thereto through a suitable friction clutch.

Referring now particularly to Figs. 2 and 5, there is shown a motor 48, driving shaft 75 49 and pinion 50 carried thereby cooperating with a gear wheel 51 for imparting motion to the power shaft 44 of the receiving printer. Power is communicated from the driving shaft to the driven shaft by means 80 of a friction clutch 52. The construction of the friction clutch 52 is as follows: Mounted on the side of the gear wheel 51 is a series of posts 54 on which there is arranged a plurality of plates 55, 56, 57 and 58, adapted to rotate with the gear wheel 51. Rigidly secured to the power shaft 44 is a plurality of discs 59, 60, 61 and 62 of a lesser diameter than that of the plates carried by the posts 54. Intermediate the plates which are carried by the posts 54 and the discs carried by the driven shaft 44 is a series of friction discs 63 which may consist of wood or any desired material. Mounted on the end of the shaft 44 is an extension carrying a number of threads designed to receive a nut 64. In order that the pressure between the various plates may be varied, there is interposed between the nut 64 and the plate 59 a helical spring 65.

Also carried to the posts 54 is another series of plates 66 and 67 forming a part of a second clutch 69. Rigidly mounted on the shaft 20 and interposed between the two plates 66 and 67 is a disc 68 of a smaller diameter than the plates 66 and 67. Interposed between the plates 66 and 67, which are rigidly secured to the posts 54 and the plate 68, which is mounted on the shaft 20, is a series of friction discs 75. These discs, as described in connection with the clutch 52, may consist of wood or any desired material. For adjusting the pressure between the several parts of the clutch 69, a coiled spring 70 is placed between the plate 67 and 105 adjustable blocks 71 which are slidably mounted on the posts 54.

From the description pertaining to the 110 clutches 52 and 69, it is seen that but one source of motive power 48 is required for driving the shaft of the distributor and the receiving printer, respectively. This feature is particularly advantageous since it enables the mounting of the distributor equipment and the printer as a unit. It not only affords better operating characteristics, but also diminishes to a considerable extent the space occupied by the separate units. In order to compensate for line lag or what 115 is sometimes known as line distortion, the 120 125 130

distributing mechanism is equipped with means whereby the interval of time elapsing between the release of the distributor brush arm and its engagement with the first contact may be varied. With such an arrangement the impulses transmitted from the distant station will be received, in cases where the distributor is acting as a receiving distributor, in a manner such that the signals will be properly distributed to the printer mechanism with which the distributor is associated. In the present instance, this is accomplished by having the part of the mechanism carrying the release magnets and the release latch rotatable about a portion of the hub 26. Normally the portion carrying the release magnets and the release latch is held against rotation due to the force applied through the thumb screw 72 upon the extension 12 which engages a portion of the hub 26. When it is desired to orient the brush arm it only becomes necessary to loosen the thumb screw 72 and rotate the release magnet with its release latch in a direction determined by whether it is desired to have the brush arm 19 engage the contacts at a time sooner or later than when the release latch is in its normal or zero position. When the thumb screw 72 is rotated in a counter clock-wise direction, the extension 12 can thereby be freely shifted on the bearing or hub 26 to any desired position. To indicate the amount of displacement a suitable scale 73 graduated upon plate 10 and a binder 74 are provided. With such an arrangement it is possible to orientate the distributors to the smallest increment to compensate for any line lag.

The present invention has been illustrated and described as applied to a distributor of the start-stop type. Obviously, though, the same principle may be readily employed in other types of distributors, such as, for example, those in which the contact arm is continuously rotating without departing from the spirit and scope of the invention.

What is claimed is:

1. A distributor for printing telegraphs comprising a plurality of spring contact members, actuating means normally tending to rotate, means for releasing said actuating means to operate said spring contact members in succession, and means for permitting of a variation between the time of release of said actuating means and its operation of the first spring contact members.

2. The combination with a power shaft normally tending to rotate, of a distributor comprising a plate, a series of spring contact members having open and closed positions arranged concentrically on said plate, an arm normally tending to rotate, electrically operated means for releasing said arm whereby said contact members will be actuated to their closed position in succession,

and a mechanical means operated automatically on each revolution of said arm for releasing said power shaft.

3. The combination of a pair of shafts arranged to be driven, a common source of motive power for driving said shafts, coupling means intermediate said shafts and source of motive power, means for restraining the movement of said shafts, a series of spring contact members, means secured to one of said shafts for actuating said contact members in succession, and means controlled by the rotation of the shaft carrying said arm for releasing the restraining means on the other of said shafts.

4. The combination with a pair of shafts arranged to be driven, of a common source of motive power for said shafts, coupling means intermediate said shafts and source of motive power, means for restraining the movement of said shafts, a series of circuit closing means, a contact arm secured to one of said shafts for effecting the operation of said circuit closing means in succession, and further means responsive to each revolution of the shaft carrying said contact arm for releasing the restraining means on the other of said shafts.

5. A distributor comprising a series of flexible spring contact members having open and closed positions arranged concentrically, a shaft normally tending to rotate, means secured to said shaft, and means responsive to current impulses for releasing said shaft whereby said means is caused to move the spring contact members to their closed position in succession.

6. A distributor comprising a series of spring contact members having open and closed positions arranged concentrically, a shaft, contact means rigidly secured to said shaft, a latch for holding said contact means and shaft against rotation, means responsive to current impulses for operating said latch whereby said contact means is released for moving said contact members to their closed position in succession.

7. A distributor comprising a series of spring contact members having open and closed positions arranged concentrically, a contact arm normally tending to rotate for actuating the spring contact members to their closed position, and electrically operated means for periodically releasing said contact arm for rotation.

8. A distributor comprising a series of spring contact members having open and closed positions arranged concentrically, a contact arm normally tending to rotate for actuating the spring contact members to their closed position, and an electromagnet responsive to current impulses for periodically releasing said contact arm for rotation.

9. A distributor comprising a series of

spring contact members arranged concentrically, a contact arm normally tending to rotate for actuating the spring contact members, electrically operated means for periodically releasing said contact arm for rotation, a power shaft, means for holding said shaft against rotation, and a cam operated

in synchronism with said contact arm for mechanically operating said holding means.

In witness whereof I hereunto subscribe my name this 10th day of November, A. D., 1920.

MERLE P. CHAPLIN,
